UNITED STATES PATENT OFFICE.

WILLIAM H. BAKER, OF CENTRAL FALLS, RHODE ISLAND, AND FREDERIC E. KIP, OF MONTCLAIR, NEW JERSEY.

LOOM.

SPECIFICATION forming part of Letters Patent No. 655,648, dated August 7, 1900.

Application filed March 21, 1900. Serial No. 9,493. (No model.)

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have invented certain new and useful Improvements in Looms, of which the following is a specification.

This invention relates to looms having means for replenishing weft or filling automatically, and particularly to what are known as "double-shuttle" looms, wherein two shuttles, one above the other, are picked simultaneously through the sheds in the warps.

According to the present invention two shuttle-boxes are superposed and open at the sides, and the shuttles are also open at the sides instead of at top and bottom. The weft-cases or weft-holders, such as bobbins or bobbins in bobbin-cases, are mounted detachably in an upright endless-chain carrier which constitutes a magazine and are brought in front of the shuttles in the shuttle-boxes, drivers being employed to drive full weft-holders laterally from the chain-carrier of the magazine or holder into the shuttles as required, means for operating said drivers being controlled by the presence or absence of weft or filling on the weft-holders in the respective shuttles.

In the accompanying drawings, which illustrate the invention, Figure 1 is a side elevation of a part of the loom illustrating the invention, and Fig. 2 is a front elevation of the same. Fig. 3 is a sectional elevation, on a larger scale, illustrating the construction of the magazine, shuttle-boxes, and adjacent parts. Fig. 4 is a section at the axial line A in Fig. 3. Fig. 5 is a detail view of the chain-guide, showing the guide and chain in horizontal section on a relatively-large scale. Fig. 6 is a vertical longitudinal section of a shuttle-box, showing the shuttle therein in side elevation. Fig. 7 is a horizontal axial section of the shuttle. Fig. 8 is a front face view of the shuttle-boxes and lay, illustrating the electrical connections. Figs. 9, 10, 11, and 12 illustrate a mechanical controlling device with an automatic feeler, which device may be substituted for the electrical controlling device of the principal views. Fig. 9 is a side

view of the device. Fig. 10 is a front view thereof. Fig. 11 is a plan view thereof; and Fig. 12 is a view of the shuttle and bobbin or weft-holder, showing the indicator on the latter.

a represents the loom-frame. *b* is the breast-beam forming a part thereof. *c* is the lay, which may be provided with two race-ways *c' c²*, as shown in Fig. 8. *d* shows the lay-swords. *e* is the picker-stick, and *f* is the shaft from which the lay receives its vibrations through cranks and connecting-rods in the usual way. These parts are all common in looms and may be of the usual kind.

On the lay are mounted the two shuttle-boxes *g g'*, open at the sides and provided each with a swell *h* at its top, as seen in Fig. 6. There will be of course a pair of superposed shuttle-boxes at each side of the loom; but only the pair at the side where the shuttles are supplied is herein shown. The boxes in this pair are alike and are distinguished only by *g* designating the upper box and *g'* the lower. In these boxes are the shuttles *i*, which are also alike. Each shuttle is open at its sides, so that an exhausted weft-holder therein may be driven out at one side by a full weft-holder entering at the other side. On the loom-frame is mounted in suitable bracket-supports *j* the magazine to contain the weft-holders. This magazine is designated as a whole by *M*, and it consists, essentially, of an upper pair of sprocket-wheels *k*, a lower pair of sprocket-wheels *k'*, and an endless-chain carrier *l*, mounted on said sprocket-wheels and provided with spring-clips *m* to hold in place the weft-holders. In the drawings this weft-holder is a metal bobbin-case *n*, containing a bobbin *o*, as seen best in Figs. 6 and 7. The chain-carrier of the magazine is advanced step by step to bring the weft-holders as needed opposite to the shuttles in the shuttle-boxes, the movement being, as herein shown, upward at the delivery side of the carrier next to the shuttle-boxes. The movement of the carrier is effected through the medium of a slip-belt *p*, driven by a pulley *q* on the crank-shaft *f* of the loom, said belt passing about a pulley *r*, Fig. 4, loose on the boss of the upper pair of sprocket-wheels *k*, being connected to said boss through a

spring s , which is wound or put under tension by the belt p , working frictionally on the pulley r . When the chain-carrier is restrained by a detent, (to be described,) the belt p winds 5 up the spring s until the tension thereof overcomes the friction of the belt, when the latter slips. A specific device of this character for constantly tending to rotate a magazine containing weft is illustrated in our pending application, Serial No. 4,221, filed February 6, 1900, and is not specifically claimed herein.

A detent device holds the chain-carrier against movement until a weft-holder is driven therefrom into the shuttle and then 15 permits the carrier to advance to the extent of one weft-holder, so that the next weft-holder in succession takes the place of that displaced. The preferred form of detent t is best illustrated in Figs. 3 and 4. It is in the 20 nature of a rocker pivotally mounted on the bracket supporting the magazine and having two arms which take over from behind the two bobbin-cases that occupy positions at the delivery-point. So long as both of these bob- 25 bin-cases are in position in the chain-carrier the latter is held against movement; but if either bobbin-case be displaced the detent is free to rock and allow the other bobbin-case to wipe past; but as the next succeeding bob- 30 bin-case comes into position the two will wipe into their places in the detent and lock the chain against further movement. For example, if the upper bobbin-case be driven into the upper shuttle the chain-carrier will 35 move up to the extent of one bobbin-case; but if the lower of the two bobbin-cases be driven into the lower shuttle the chain-carrier will move up to the extent of two bobbin-cases. The extent of movement of the rock- 40 ing detent t is limited by an arm on the back thereof playing between two studs on the supporting-bracket. This arm is sufficiently indicated by dotted lines at u in Fig. 3.

The means for driving the weft-holders into 45 the respective upper and lower shuttles are the drivers v and v' , which are pivotally mounted at w on the loom-frame. These hammers are actuated by the lay in beating up through the medium of a dagger or tappet x thereon. 50 The drivers are situated side by side, and to them below the common pivot or fulcrum w are coupled or hinged, respectively, arms y and y' , which rest, respectively, on the armature-levers of two electromagnets z and z' . 55 The drivers are held drawn back normally by any form of springs 1, and the usual springs uphold and retract the armature-levers of the electromagnets normally. While the armature-levers are thus upheld the arms y and 60 y' are elevated and held above the path of the tappet x ; but if either magnet be excited it will attract its armature, draw down its lever, and thus permit the arm y or y' , which it supports, to descend into the path of the 65 tappet x , so that when the loom beats up the driver coupled to that arm will be actuated. Figs. 1 and 4 show the lay beat up under nor-

mal conditions or when no fresh supply of weft is required.

The means whereby the excitation of either 70 of the electromagnets is controlled by the substantial absence of weft on the shuttle in play may be effected in any known way. We have illustrated herein, Fig. 7, the construction for this purpose which is shown and claimed in 75 our pending application, Serial No. 411, filed January 5, 1900, and this construction will now be briefly described, premising, however, that as each shuttle, shuttle-box, bobbin-case, &c., is fitted up in the same manner a description of one of each will suffice for all, and premising also that the electrical devices employed are substantially duplicated, one for the upper box and one for the lower. Reference may be had especially to Figs. 6, 7, 85 and 8.

The bobbin-case n is of metal, preferably (but not necessarily) cylindrical and in two sections telescoping and insulated from each other at 2. This case is held in the shuttle 90 by metal spring-jaws 3 in the shuttle at each end of the cavity therein. In the bobbin-case is hinged a metal spindle 4 to receive the bobbin o . On this spindle is a spring 5 and a metal washer 6, which is electrically connected by suitable conductors with a metal plate 7 in the bottom of the shuttle at that end. At the other end of the shuttle the spring-jaws 3 are electrically connected with a similar metal plate 7^a. When the shuttle 100 enters its box, the respective plates 7 and 7^a are put into contact with terminals 8 8^a, Fig. 6, of an electric circuit, including conductors 9, a generator 9^a, and one of the electromagnets z or z' . Fig. 8 is a diagrammatical view 105 showing the two circuits.

The bobbin o , which may be of wood, has at its end a metal ring or piece 10, which is in contact with the washer 6 on the spindle, and from this ring 10 projects a spring 11, 110 which takes under and presses outward radially a metal indicator 12, hinged in a slot in the bobbin, with its free end adapted to be pressed into contact by the spring 11, with the inner surface of a flanged outer 115 metal ring 13 on the bobbin. The weft or filling on the bobbin overwraps an arched portion of the indicator 12, however, and holds its free end out of contact with the ring 13 normally. When the bobbin is slipped onto the spindle, the flange on the ring 13 takes over and is in electrical contact with a 120 spring-blade 14 on the right-hand section of the bobbin-case as the construction is illustrated in Fig. 7. It will be seen without further description that when the shuttle enters its box the circuit will always be completed, except between the indicator 12 and the ring 13, and that when the weft or filling on the bobbin shall have become nearly exhausted the 125 spring 11 will be permitted to press the indicator 12 out into contact with the ring 13, so that when the shuttle next enters the box at the same side of the loom as the magazine the 130

circuit will be completed through the magnet and the arm y or y' lowered into the path of the tappet x . Consequently when the lay beats up the driver will drive a fresh bobbin-case into the shuttle and expel the exhausted one therefrom.

On the bobbin-cases n and near the ends of the same are placed cushions or pads 15, of rubber or other soft material, to cushion the blow of one case on the other, and each case will have a hole 16 in its side to lead out the weft end. The magazine will have a suitable weft-end holder which moves with the carrier, and this may be constructed as best seen in Figs. 1, 2, and 4. A shaft 17 is mounted rotatively in the bracket j , centrally between the axes of the sprocket-wheels, and geared to the upper sprocket-wheel shaft for driving by sheaves 18 and 19 and a belt 20. On the outer end of this shaft is the weft-end holder 21, to which the weft ends are led out and attached. The sheaves 18 and 19 are properly proportioned to give to the holder 21 the proper speed.

In order to keep the chain-carrier l properly alined at the delivery-point and to provide a resistance for the blows of the drivers, there are fixed upright guides 22, carried by the bracket or brackets supporting the magazine. Fig. 5 shows one of these guides 22 in detail.

It will be understood that while we have shown electrical controlling devices similar to that shown in our before-mentioned pending application we do not limit ourselves in this respect. We may employ mechanical controlling means including a feeler—for example, such as that illustrated in our pending application, Serial No. 4,221, filed February 6, 1900.

In Figs. 9, 10, 11, and 12 we have illustrated the adaptation of the feeler device of our copending application, Serial No. 4,221, to a double-shuttle loom, and this device will now be described. Mounted in bearings on the face of the lay are two rock-shafts 23 and 23^a, one being tubular and the other passing through it. On each shaft is a pair of lugs 24, in which is hinged a tappet 25, supported somewhat elastically by a spring-blade 26. By rocking either of said shafts the tappet 25 carried thereby may be put in position, so that when the lay beats up said tappet will impinge upon a toe v^x on the opposite driver.

There are two of these toes situated side by side, and each tappet is adapted to strike one of the toes. On the respective rock-shafts 23 and 23^a are crank-arms 27 and 27^a, from which extend upward connecting rods or links 28 and 28^a, coupled at their upper ends to crank-arms 29 and 29^a on two rock-shafts 30 and 30^a on the sides of the respective superposed shuttle-boxes. As each box is fitted up in the same way it will only be necessary to describe one, with especial reference to Fig. 11. The rock-shaft 30 has on it an arm 31, which loosely engages a feeler-lever 32,

adapted to swing about a pivot on the lay. The curved free end of the feeler-lever is adapted to enter the shuttle-box and the shuttle therein. A spring 33 on the shaft tends so to rock the latter as to cause the feeler to enter into the shuttle and box and also to elevate the tappet 25 through the connecting-link. When the lay swings back or recedes to the picking and receiving position, the lower rock-shaft is rocked, so as to withdraw the feeler from the shuttle and box, and this is effected by means of a fixed dagger q on the loom-frame, which impinges on arms 34 on the respective rock-shafts 23 and 23^a. On the lower side of the shuttle, Figs. 11 and 12, is pivotally mounted a feeler-finger 35, which is in the path of the feeler-lever. A spring 36 on the shuttle bears on the shorter arm of the finger 35 and holds the longer arm of the latter pressed up to a stop 37, as seen in Fig. 12, normally; but when the feeler-lever strikes said finger it swings the latter into the shuttle, under the weft-holder m' therein, so that if the indicator 12' in the latter be protruded the finger will impinge thereupon and be limited in its movement thereby, as explained in our said application. The operation is precisely the same as illustrated in our said copending application, and the stationary dagger q for withdrawing the feeler-lever will be the same as in the said application.

In lieu of employing bobbin-cases containing bobbins we may mount the bobbins themselves directly in the spring-clips in the magazine, in which case self-threading shuttles, such as are now known in the art, would be employed. We have not deemed it necessary to illustrate these departures from the construction illustrated, as they will be obvious to any one skilled in the art to which this invention pertains.

We are aware that double-shuttle looms supplying from two separate magazines full shuttles to the raceway are not new; but as we are the first, as we believe, to supply a weft-holder containing a fresh supply of weft or filling into either or both of the active shuttles as they require to be replenished with said weft or filling during the same pick of the loom and also to supply weft for both sheds from a single magazine we claim same broadly and do not limit ourselves to any specific construction for accomplishing this result, as same may be varied considerably. We would consider our invention practiced in a double-shuttle loom having weft or filling supplying mechanism wherein weft or filling is supplied from a single magazine to one or both of the warp-sheds, as required, during the weaving.

By "weft-holder" or "bobbin" as herein expressed is meant any known device on which weft or filling is wound, and by "weft-case" or "bobbin-case" as herein expressed is meant any receptacle adapted to go into a shuttle containing weft or filling.

By "absence" or "substantial absence" and by "exhaustion" or "substantial exhaustion" of weft or filling from shuttles in play as is herein expressed is not necessarily meant the entire absence of said weft or filling, but such degree of exhaustion thereof as will permit the exhaustion-indicating devices to perform their functions without an imperfection being made in the cloth.

10 Having thus described our invention, we claim—

1. In a loom, the combination with a shuttle-box and shuttle adapted to receive and discharge weft-holders laterally, of an endless-chain carrier movable substantially vertically adjacent to said shuttle-box, means for moving said carrier, a detent for arresting the movement of said carrier, weft or filling holders mounted in said carrier, a driver for driving said holders from the carrier into the shuttle, means for operating said driver, and means controlled by the presence or absence of weft in the shuttle for setting said driver in operation.

15 2. In a loom, the combination with a shuttle-box and shuttle adapted to receive and discharge weft-holders laterally, of an endless-chain carrier movable substantially vertically adjacent to said shuttle-box, means for moving said carrier, a detent for arresting the movement of said carrier, weft or filling holders mounted in said carrier, a driver for driving said holders from the carrier into the shuttle, means for operating said driver, and electromagnetic means controlled by the presence or absence of weft in the shuttle for setting said driver in operation.

20 3. In a loom, the combination with two superposed shuttle-boxes, and shuttles, both

40 adapted to receive and discharge weft-holders laterally, and means for picking the shuttles from said boxes simultaneously, of a magazine comprising an endless-chain carrier movable substantially vertically and provided with means for supporting weft-holders, means for moving said carrier, a detent for holding said carrier against movement normally with weft-holders opposite the superposed shuttle-boxes, two drivers for driving the weft-holders from the carrier into the respective boxes, means for actuating said drivers at proper times, and means controlled by the presence or absence of weft or filling in the respective shuttles for setting said drivers in operation.

45 5. In a loom, the combination with two superposed shuttle-boxes, and shuttles, both

50 adapted to receive and discharge weft-holders laterally, and means for picking the shuttles from said boxes simultaneously, of a magazine comprising an endless-chain carrier movable substantially vertically and provided with means for supporting weft-holders, means for moving said carrier, a detent for holding said carrier against movement normally with weft-holders opposite the superposed shuttle-boxes, two drivers for driv-

ing the weft-holders from the carrier into the respective boxes, means for actuating said drivers at proper times, and electromagnetic means controlled by the presence or absence of weft or filling in the respective shuttles for setting said drivers in operation.

5. In a loom, the combination with two superposed shuttle-boxes, and shuttles, both adapted to receive and discharge weft-holders laterally, and means for picking the shuttles from said boxes simultaneously, of a magazine comprising an endless-chain carrier movable substantially vertically and provided with means for supporting weft-holders, means for moving said carrier, the automatic rocking detent for holding said carrier against movement normally with weft-holders opposite the superposed shuttle-boxes, two drivers for driving the weft-holders from the carrier into the respective boxes, means for actuating said drivers at proper times, and means controlled by the presence or absence of weft or filling in the respective shuttles for setting said drivers in operation.

6. In a loom, the combination with the magazine, comprising the upper and lower pairs of sprocket-wheels and the endless-chain carrier provided with means for supporting weft or filling holders, of the fixed guides 22, the rocking detent, means for transferring the weft-holders from the magazine to the shuttle, and means for driving said carrier.

7. In a loom, the combination with the upper and lower pairs of sprocket-wheels, the endless-chain carrier thereon, and means for driving said carrier, of the weft-end holder on the shaft 17, the said shaft, and means for driving said shaft in unison with the movements of the carrier.

8. The combination with a loom having two raceways and two shuttles, of a movable feeder or magazine for weft-holders, said weft-holders being adapted to go into the shuttles, consisting of an endless-chain carrier having means for supporting a series of said weft-holders, means for rotating said magazine, means for restraining at proper times said rotation of the magazine and means for driving as required, from said magazine, into the shuttles in play at the same pick of the loom, either one or two of said weft-holders, substantially as set forth.

9. In a double-shuttle loom, the combination with means for picking the shuttles through two warp-sheds, a movable magazine or feeder, for weft-holders, same consisting of an endless chain having devices for supporting a plurality of weft-holders, means for transferring as required either one or two weft-holders at the same time, from the said magazine to either or both of the shuttles in play, the time of operation of said supplying mechanism being controlled by the presence or absence of weft or filling in the shuttles in play.

10. In a double-shuttle loom, the combination with means for picking the shuttles

- through two warp-sheds, a movable magazine or feeder for weft-holders, same consisting of an endless chain having devices for supporting a plurality of weft-holders, means for transferring, as required, one or two weft-holders at the same time from the said magazine, to either or both of the shuttles in play, means for controlling the times of operation thereof, said means consisting of an electric circuit connected with said supplying mechanism and made inoperative and operative, respectively, by the presence or substantial absence of weft or filling in the shuttles in play.
11. In a loom, the combination with two superposed shuttle-boxes, and means for picking two shuttles through two warp-sheds at about the same time, of a single magazine, and means for supplying from said magazine either or both of said shuttles with a weft-holder containing a supply of weft or filling in place of that substantially exhausted, the times of operation of said supplying mechanism being controlled by the presence or substantial absence of weft or filling in the shuttles in play.
12. In a loom, the combination with two superposed shuttle-boxes, and means for picking two shuttles through two warp-sheds at about the same time, of a single magazine, means for supplying from said magazine either or both of said shuttles with a weft-holder containing a supply of weft or filling in place of that substantially exhausted, and means for controlling the times of operation thereof, said means consisting of an electric circuit connected with said supplying mechanism and made inoperative or operative, respectively, by the presence or substantial absence of weft or filling in the shuttles in play.
13. In a weft-supplying mechanism, the combination with means for picking shuttles through two warp-sheds at about the same time, a single feeder or magazine adapted to carry a reserve supply of weft-holders for both shuttles and two drivers adapted to drive or push in the same pick of the loom as required, either or both of the weft-holders that may be in their path into either or both of the shuttles, substantially as set forth.
14. In a weft-supplying mechanism, the combination with means for picking shuttles through two warp-sheds, at about the same time, a single feeder or magazine adapted to carry a reserve supply of weft-holders for both shuttles, two drivers adapted to drive or push, as required, either or both of the weft-holders before them into either or both of the shuttles during the same pick of the loom, and means connected with said feeder or magazine for always presenting to the proper delivery position two weft-holders, independent of whether one or two of said weft-holders have been previously transferred from said magazine to the shuttles, the time of operation thereof being controlled by the presence or substantial absence of weft or filling in the shuttles in play.
15. In a weft-supplying mechanism, the combination with means for picking shuttles through two warp-sheds at about the same time, a single feeder or magazine adapted to carry a reserve supply of weft-holders for both shuttles, two drivers adapted to drive or push as required, either or both of the weft-holders before them into either or both of the shuttles during the same pick of the loom, means connected with said feeder or magazine for always presenting to the proper delivery position two weft-holders, independent of whether one or two of said weft-holders have been previously transferred from said magazine to the shuttles, and means for controlling the times of operation of the supplying mechanism, said means consisting of an electric circuit connected with said supplying mechanism and made inoperative by the presence, and operative by the substantial absence, of weft or filling in the shuttles in play.
16. In a weft or filling supplying mechanism for looms, the combination with means for traversing two shuttles, through two warp-sheds at each pick of the loom, a feeder or magazine containing a reserve supply of weft or filling in the form of weft-holders, means for transferring the weft-holders from the magazine to the shuttles, means for rotating said magazine and a restraining device preventing, periodically, said rotation, said restraining device being made operative when two of the said weft-holders engage it, and inoperative on either one or both of said weft-holders being removed from said engagement, substantially as set forth.
17. In a weft or filling supplying mechanism for looms, the combination with means for traversing two shuttles, through two warp-sheds at each pick of the loom, a feeder or magazine containing a reserve supply of weft or filling in the form of weft-holders, means for transferring the weft-holders from the magazine to the shuttles, means for rotating said magazine and a restraining device preventing periodically said rotation, said restraining device being made operative when two of the said weft-holders engage it, and inoperative on either one or both of said weft-holders being removed from said engagement, the time of transferring said weft holder or holders from the magazine to the shuttle or shuttles being controlled by the presence or substantial absence of weft or filling in the shuttles.
18. In a weft or filling supplying mechanism for looms, the combination with means for traversing two shuttles through two warp-sheds at each pick of the loom, a feeder or magazine containing a reserve supply of weft or filling in the form of weft-holders, means for rotating said magazine and a restraining device preventing periodically said rotation, said restraining device being made operative

when two of the said weft-holders engage it, and inoperative on either one or both of said weft-holders being removed from said engagement, combined with drivers adapted to transfer said weft-holders from the magazine to the shuttles in play, and means for controlling the time of operation thereof, said means consisting of an electric circuit connected with said supplying mechanism and made inoperative and operative, respectively, by the presence or absence of weft or filling in the shuttles in play.

19. In a weft or filling supplying mechanism for looms, the combination with means for picking two shuttles through two warp-sheds at each pick of the loom, a single feeder or holder containing a reserve supply of weft or filling for both shuttles, said holder consisting of an endless-chain carrier having means for supporting weft-holders, mechanism for transferring the weft-holders from the magazine to the shuttles, and a restraining device preventing, periodically, the shifting of the holder, said restraining device being made operative when two of the said weft-holders engage it, and inoperative when either one or both of said weft-holders is removed from said engagement, substantially as set forth.

20. In a weft or filling supplying mechanism for looms, the combination with means for picking two shuttles through two warp-sheds at each pick of the loom, a single feeder or holder containing a reserve supply of weft or filling for both shuttles, said holder consisting of an endless-chain carrier having means for supporting weft-holders, mechanism for transferring the weft-holders from the magazine to the shuttles a restraining device preventing, periodically, said rotation of the holders, said restraining device being made operative when two of the said weft-holders engage it, and inoperative when either one or both of said weft-holders is removed from said engagement, and means whereby the time of transferring said weft holder or holders from the holder to the shuttle or shuttles is controlled by the presence or absence of weft or filling in the shuttles.

21. In a double-shuttle loom having superposed shuttle-boxes, the combination with means for picking two shuttles at each pick through the warp-sheds, a feeder or magazine containing a reserve supply of weft or filling, said magazine consisting of an endless-chain carrier having means for supporting weft-holders, means for moving said magazine to bring the weft-holders to the delivery-point, and a restraining device for preventing periodically said movement, of driving or pushing mechanism adapted to drive or push said weft-holders from the magazine into the shuttle or shuttles and means for actuating said driving or pushing mechanism, at the same pick of the loom, to supply as required either one or both of the shuttles with a new supply of weft or filling to replace that substantially exhausted.

22. In a weft or filling supplying mechanism, the combination with means for picking two shuttles at each pick through the simultaneously-formed warp-sheds, a feeder or magazine containing a reserve supply of weft or filling, said magazine consisting of an endless-chain carrier having means for supporting weft-holders, means for moving said magazine to bring the weft-holders to the delivery-point, and a restraining device for preventing periodically said movement, of driving or pushing mechanism adapted to drive or push said weft-holders from the magazine into the shuttle or shuttles and electromechanical means for actuating said driving or pushing mechanism, at the same pick of the loom, to supply as required either one or both of the shuttles with a new supply of weft or filling to replace that substantially exhausted.

23. In a double-shuttle loom having means for forming at about the same time two superposed warp-sheds, and having two shuttles adapted to be picked therethrough, the combination with a single magazine adapted to carry a reserve supply of weft or filling, of means for automatically furnishing therefrom weft or filling to either or both of said warp-sheds, as required, to replace that substantially exhausted, the time of operation of said supplying mechanism being controlled by the presence or substantial absence of weft or filling in the respective shuttles in play.

24. In a double-shuttle loom having means for forming at about the same time, two superposed warp-sheds, and having two shuttles adapted to be picked therethrough, the combination with a single magazine adapted to carry a reserve supply of weft or filling, of means for automatically furnishing therefrom weft or filling to either or both of said warp-sheds, as required, to replace that substantially exhausted, and means for controlling the times of operation thereof, said means consisting of an electric circuit connected with said supplying mechanism and made inoperative or operative, respectively, by the presence or substantial absence of weft or filling in the respective shuttles in play.

25. A rotatively-mounted feeder or magazine, consisting of an endless chain, having means for carrying a reserve supply of weft or filling, and a support to steady the chain at the delivery-point combined with a weft-end holder, means for rotating said endless chain and means for rotating said weft-end holder in unison with the rotation of the endless chain, substantially as set forth.

26. A rotatively-mounted feeder or magazine, consisting of an endless chain having means for carrying weft-holders, adapted to go into shuttles, combined with a rotatable weft-end holder having its shaft separate from that of the magazine, means for rotating said endless chain, and means for rotating said weft-end holder in unison with the rotation of the endless chain, substantially as set forth.

27. A rotatively-mounted feeder or magazine, consisting of an endless chain having two sprocket-wheels, the links of the chain having means for carrying a reserve supply 5 of weft or filling, and a support to steady the chain, situated at the delivery-point, combined with a weft-end holder, means for rotating said endless chain and means for rotating said weft-end holder in unison with the 10 rotation of the endless chain, substantially as set forth.

28. A rotatively-mounted feeder or magazine, consisting of an endless chain having two sprocket-wheels, the links of the chain 15 having means for holding and carrying weft-holders, combined with a weft-end holder having its shaft separate from that of the magazine, means for rotating said endless chain, and means for rotating said weft-end holder 20 in unison with the rotation of the endless chain, substantially as set forth.

29. In a loom, means for traversing two shuttles through two warp-sheds, two superposed shuttle-boxes, a weft or filling replenishing 25 mechanism comprising a feeder or magazine containing a reserve supply of weft-holders, means for transferring the weft-holders from the magazine to the shuttles, means for moving said magazine and a restraining device 30 that periodically restrains said movement, said restraining device being inoperative to the extent of the space occupied in said magazine by one weft-holder when a weft-holder is supplied to the upper shuttle in play, and 35 inoperative to the extent of the space occupied in the magazine by two weft-holders when a weft-holder is supplied to the lower shuttle or to both the lower and the upper shuttles in play, and electromechanical means 40 made inoperative and operative, respectively, by the presence or substantial absence of weft or filling in the shuttles in play, for controlling the times of operation of said mechanism.

45 30. In a weft or filling supplying mechanism for looms, the combination with means for picking two shuttles through two warp-sheds at each pick of the loom, a feeder or holder containing a reserve supply of weft or filling, 50 said holder consisting of an endless-chain carrier having means for supporting weft-holders, means tending to rotate said holder, a restraining device that periodically restrains said rotation, said restraining device 55 being inoperative to the extent of the space occupied in the holder by one weft-holder

when a weft-holder is supplied to the upper shuttle in play, and inoperative to the extent of the space occupied in the magazine by two weft-holders when a weft-holder is supplied 60 to the lower shuttle or to both the lower and upper shuttles in play, means for transferring the weft-holders from the feeder to the respective shuttles, and electromechanical means made inoperative by the presence, and 65 operative by the substantial absence of weft or filling in the shuttles in play, for controlling the times of operation of said replenishing mechanism.

31. In a weft-supplying mechanism for 70 looms, the combination with means for picking two shuttles through two warp-sheds at each pick of the loom, a movable magazine adapted to hold and carry weft-holders, means for transferring, as required, on the same 75 pick of the loom, from said magazine to the respective shuttles, either one, or two adjoining weft-holders, of a detent for arresting the rotation of the magazine, said device comprising two stops so spaced as to bear on contiguous or next adjoining weft-holders in the magazine, and exhaustion-indicating devices made inoperative by the presence, and operative by the substantial absence of weft or filling in the shuttles in play, which control 80 the times of operation of said mechanism.

32. In a weft-supplying mechanism for 90 looms, the combination with means for picking two shuttles through two warp-sheds at each pick of the loom, a movable chain-carrier, or magazine adapted to hold and carry weft-holders, means for transferring, as required, on the same pick of the loom, from said magazine to the respective shuttles, either one or two adjoining weft-holders, of 95 a detent for arresting the rotation of the magazine, said device comprising two stops so spaced as to bear on contiguous or next adjoining weft-holders in the magazine, and exhaustion-indicating devices made inoperative by the presence, and operative by the substantial absence of weft or filling in the shuttles in play for controlling the times of 100 operation thereof.

In witness whereof we have hereunto signed 105 our names, this 12th day of March, 1900, in the presence of two subscribing witnesses.

WILLIAM H. BAKER.
FREDERIC E. KIP.
